UNITED STATES PATENT OFFICE

JOHN P. KEEFE, OF MANCHESTER, NEW HAMPSHIRE, ASSIGNOR TO INTERNATIONAL SHOE COMPANY, OF ST. LOUIS, MISSOURI, A CORPORATION OF DELAWARE

MANUFACTURE OF BOOTS AND SHOES

Application filed January 23, 1929. Serial No. 334,488.

This invention relates to the manufacture of boots and shoes and more particularly to a method of attaching heels including also the preparation of a channeled outsole in a manner to eliminate injury to the sole edges forward of the heel breast. By way of example the disclosure herein will deal with the application of the principles of the invention to the manufacture of women's McKay shoes having wood heels, but this is not a limitation.

Heretofore the heel seats of outsoles have generally been fitted by hand to facilitate the attachment of wood heels. The outsole, when applied to the shoe, has been of the usual type and the fitting operations have consisted in cutting away the margin of the heel seat stock to form a tongue which will permit the edge of the heel to engage the upper, and also forming at the breast line two transverse shoulders for the same purpose, one at each side of the tongue left by the marginal cut. The shoulders may be used to gage the position of the heel on the shoe just prior to its attachment. Surface stitching is not the practice for McKay shoes and consequently the outsole is channeled and the McKay seam is covered by the channel flap. The channeling machine cuts the channel rearward beyond the breast line so that in fitting the heel seat, as above described, the flap as well as the marginal stock beneath it is severed and removed when making the two shoulder cuts. This leaves two free ends on the channel flap, one at each breast corner, that are unsecured except by cement. While the shoe is in use the edges of these channel flap ends frequently become loosened from the sole stock because of wetting, a blow at this point or one of the other hazards of wear and the shoe becomes unsightly. An acceptance of this condition does not constitute fine shoemaking.

The object of the present invention is to devise a process of manufacture, including a novel fitting of the outsole, that will eliminate all danger of a picked-up channel flap at the breast corners of the heel even though the cement fails to hold.

To the accomplishment of this object and

such others as may hereinafter appear, as will readily be understood by those skilled in the art, the invention comprises the features and combinations of parts and processes of manufacture hereinafter described and then particularly pointed out in the appended claims. The features and scope of the invention will best be understood from a description of the preferred embodiment thereof illustrated in the accompanying drawings, in which:

Figure 1 is a view, in perspective, of a channeled outsole having the novel heel seat fitting of the invention;

Fig. 2 is a view, in plan, of the flesh side of the heel seat of the outsole shown in Fig. 1 with its channel laid;

Fig. 3 is a view, in perspective, of a shoe bottomed with the outsole of Fig. 1 and ready for the heel attaching operation; and

Figs. 4 and 5 are views, in plan and in side elevation, of the heel end of a shoe with a heel attached, the novel heel seat fitting of the outsole being indicated by dotted lines.

In the embodiment of the invention illustrated in the drawing an outsole 10 is dinked or rounded in a manner to form a central tongue or heel filler 12 (Figs. 1 to 3) instead of having a complete heel seat. This outsole is completely channeled, with any style of knife desired, throughout the forepart, shank and heel tongue and the continuous or unbroken channel flap 14 is raised (see Fig. 1). The margin or feather 16, exposed by raising the channel flap, is then snipped at each side of the forward end of the tongue 12 removing triangular pieces of the stock to produce two marginal, rearwardly facing shoulders 18 substantially at the breast line. The outsole is then laid and McKay stitched to the shoe as shown by Fig. 3 wherein a portion of the channel flap is lifted to show the stitching. The channel flap is now laid and it will be observed (see Figs. 2 and 3) that the flap laying operation at the heel end causes portions 20 of the flap to overlie and cover the cavity caused by the removal of stock to form the breast line shoulders 18. The shoe is now ready to have a heel 22 attached.

To locate the heel for attachment to the shoe its breast corners 24 are pressed down

upon the channel flap portions 20 overlying the relieved portions of the outsole, and the forward position of the heel is determined by its engagement with the rearwardly facing shoulders 18 which are defined, for this purpose, by the depression of the unsupported channel flap portions 20 over the shoulders and to the rear of them (see Figs. 4 and 5). The heel having been thus positioned it is attached in any usual or convenient manner (Fig. 5).

The advantage of practicing the process just described is that a channel flap is produced that extends across the breast line, i. e. it is unbroken from a point forward of the heel breast to a point rearward thereof, so that there is no loose end at the breast line that can pick up and spoil the appearance and neatness of the shank which is a highly important portion of the shoe for style effect and also much in evidence during wear. Expressed in another way, the shoulders, which provide for contact with the upper of the breast corners of the heel and which also gage its forward location, are bridged by a portion of the channel flap instead of being left bare. There is a continuity of grain surface from outside the heel to inside or beneath it, and just inside the heel this grain surface is held firmly against both the shoulder and the upper by the grip of the breast corners of the heel. As a result a neat and permanent breast corner joint is created that will not change in appearance throughout the life of the shoe. It will be observed (Fig. 4) that the puckering of the flap portions 20, as they are depressed, draws their edges inward to be completely concealed by the heel. The convex edge of the heel thus joins the upper throughout its entire length as is required for fine shoemaking.

The nature and scope of the invention having been indicated and the process of manufacture of the shoe, together with the preferred manner of fitting the outsole, having been specifically described, what is claimed as new, is:

1. The method of attaching wood heels to shoes having a short outsole with heel gaging shoulders at the ends of the breast line which comprises forming a channel flap on the outsole which overlies said shoulders and extends rearwardly thereof, and depressing said flap behind said shoulders by the pressure of the breast corners of the heel during the heel attaching operation.

2. The method of attaching wood heels which comprises fitting an outsole having a reduced heel seat with a grain channel flap cut in the margin of said heel seat at each side and continuing without a break forward of the breast line, relieving the outsole beneath said flap just rearward of each end of the breast line, positioning a wood heel with its rear edge contacting the upper and with its

breast corners at the breast line of the heel seat and on said channel flap at the points of relief, depressing said heel to depress said channel flap and extend the contact of the edge of the heel with the upper from substantially breast corner to breast corner, and attaching the heel to the shoe by permanent fastening means.

3. The method of making shoes which comprises fitting an outsole with a grain side channel having a channel flap which extends across the breast line and with a tongue at the heel end, securing said outsole to the bottom of a lasted shoe, and attaching a heel so as to cover said tongue, to engage the upper with its edge and to press upon said channel flap with its breast corners whereby said flap is prevented from lifting during wear of the shoe.

4. The method of making shoes which comprises fitting an outsole with a grain side channel having a channel flap which extends across the breast line and with the margin of its heel seat removed to produce rearwardly facing shoulders located beneath said channel flap at the breast line, securing said outsole to the bottom of a lasted shoe, and attaching a heel having its breast corners abutting said shoulders and pressing said channel flap against the upper rearward of said shoulders.

5. The method of preparing breast corner joints for wood heel attaching which comprises cutting a channel flap both forwardly and rearwardly of the breast line at each side of an outsole, turning said flap, and cutting a substantially triangular piece from the underlying stock at each side of the outsole rearward of the breast line, one side of each of said cuts being at the breast line to form a rearwardly facing breast line shoulder at each side of the outsole.

6. A wood heel shoe comprising upper materials, an outsole, a wood heel engaging the upper materials throughout substantially its edge and covering a tongue-like heel seat on the outsole, said heel being secured to said tongue, and said outsole forward of the heel being secured to the shoe by stitching beneath a marginal channel flap which extends unbroken at each side of the shank rearwardly past each breast corner of the heel and beneath the heel onto said tongue.

7. A wood heel shoe comprising upper materials, an outsole, a wood heel engaging the upper materials throughout substantially its edge and having its breast corners set against two marginal shoulders at the forward end of a tongue-like heel seat on the outsole, said heel being secured to said tongue, said outsole having a marginal channel flap extending rearwardly at each side of the shank thereof over said shoulders, under said breast corners and thence beneath the heel, and stitching beneath said channel flap forward of said heel securing the outsole to the shoe.

8. An outsole marginally channeled on its grain side from a point rearward of the breast line at one side to a similar point at the other side of its heel seat producing a continuous channel flap, and having portions of the marginal stock rearward of the breast line removed from beneath said channel flap to form two rearwardly facing breast line shoulders.

9. A short outsole for wood heel shoes having a continuous marginal channel flap on its grain side, and having triangular shaped portions of the heel seat stock removed immediately adjacent to the ends of the breast line leaving the channel flap unsupported for a short distance rearward of the breast line.

10. The method of preparing breast corner joints for wood heel attaching which comprises reducing the area of the heel end of a leather outsole from the breast line rearward, and cutting rearwardly facing shoulders, one at each end of the breast line, in the flesh only of said outsole.

In testimony whereof I affix my signature.
JOHN P. KEEFE.
